UNITED STATES PATENT OFFICE.

CLYDE H. SNOW, SR., OF MASON, MICHIGAN.

SILo CONSTRUCTION.

1,210,716.

Specification of Letters Patent. Patented Jan. 2, 1917.

Application filed November 18, 1914. Serial No. 872,767.

To all whom it may concern:

Be it known that I, CLYDE H. SNOW, Sr., a citizen of the United States, residing at Mason, in the county of Ingham and State 5 of Michigan, have invented certain new and useful Improvements in Silo Constructions, of which the following is a specification.

The invention has for an object to give an improved construction of silo which will 10 be easily erected, inexpensive and efficient, as well as durable. It is an especially important purpose to give a silo of such structural parts that a special scaffolding will not require to be erected around the structure, but will enable the support of platforms directly upon the silo while in course 15 of construction without adding to the thickness of the material beyond what is required for its normal use. Another important object is to present a construction which may 20 be adapted without change to the erection of various sizes of silos requiring no special sizes of parts for the wall erection.

Additional objects, advantages and features of invention will appear from the construction, arrangement and combination of parts hereinafter described and shown in the drawing, wherein—

Figure 1 is an elevation of one embodiment of my invention, Fig. 2 is a detail of rib structure, Fig. 3 is a detail of the door, Fig. 4 is a cross section of the silo, Fig. 5 is a detail section at the doorway, Fig. 6 is a detail elevation of the door support, Fig. 7 is a detail of one of the lugs on the ribs, Fig. 8 is a detail of a rib end, partly in section.

There is illustrated a silo comprising a number of vertical ribs 10, which may be 40 formed in sections superposed end on end, and comprising a body portion 11 of wood or other material having a rounded convex outer side, in the present instance faced with a plate 12 secured thereto in a suitable manner. The ribs are slightly wider at their 45 outer sides than at their inner sides, and are formed with recessed lateral faces rounded and faced with sheet metal 13, forming grooves 14 for the reception of the ends of 50 the panel sections 15 superposed edge to

edge and fitted snugly between the ribs whereby they are securely held against displacement. The sheet metal groove facings 13 project above the upper ends of the rib sections, and in the upper sections stop 55 short of the lower ends of the body portions 11, whereby a scarf is formed by which the joints are greatly strengthened. At each side of the plate 12 a series of vertically spaced lugs 17 are formed having horizontal transversely oblong openings 18 therethrough the sides of the lugs toward the middle of the plate being slightly convex. The major transverse dimensions of the 60 openings 18 are in a horizontal direction. (See Fig. 7.) Also spaced longitudinally of the plates 12 there are vertically apertured lugs 19 having small notches 21 centrally across their upper edge portions. Two 65 ribs are used for the door frame, one of which is formed with a door engaging edge 22 ogee-shaped in cross section extending in the mean away from the door opening toward the interior of the silo and forming a concavity in the frame at the inner edge 70 part, this one being located adjacent the pivoted side of the door. There are provided a suitable number of door sections 23 having one rounded edge adapted to fit 75 snugly in the grooved rib at one side, while the opposite side is shaped to correspond to, and fit snugly in, the ogee-shaped edge of the remaining door frame piece. These 80 door sections are preferably built of a number of narrow strips of board of suitable 85 thickness, forming two layers, those at one side being arranged vertically while those at the opposite side extend horizontally. The top and bottom edges of the door are planiform, and horizontal. The upper part of 90 each door is fitted with a spring plate 24, secured on the inner face of the door, bent abruptly over the top edge and extending outwardly beyond the front face of the door, with a slight upward inclination. The outer 95 edge portion of the plate is curved downwardly as at 25. Fixed upon each door near its right hand side, there is a pair of pivot blocks 26 on which are pivotally secured the ends of a forked arm 27, the outer 100

end of which carries a barrel 28 pivoted between the forks of an H-shaped link 29, the opposite end of which is pivoted upon a lug 30 fixed on the plate 12 at the adjacent side 5 of the door. The side of the door is inclined laterally at the inner side, so that with the rounded edge of the doors set in the groove 14 at the far side the opposite edge of the door may swing to a snug seat 10 against the correspondingly shaped door frame. With the door in this position the link 29 lies close back adjacent the plate 12 and away from the door, while the arm 27 lies closely thereover. The barrel 28 will 15 thus serve as a handle by grasping which and drawing it outwardly a considerable leverage is exerted by which the door may be cleared from the adjacent side of the frame and then swung inwardly. The door 20 is then given a sliding movement to the right and its left hand side pressed inward until it swings to the position dotted at *b* in Fig. 5, the initial movement being indicated at *a* in the same figure.

25 The door sections are provided with ladder pieces 31 spaced so as to form with the tie bars 32 a continuous series of equally spaced rungs. These tie bars are provided with right and left threads at respective ends, and are threaded into suitable lugs 33 on the plates 12 at the sides of the door. They are utilized to draw the sides of the door frame together upon the doors when closed, and may also be loosened to free the 30 doors for opening. Any other well known method may be used to draw the frame together on the bars 32, such for instance as the connections with the rods 34 hereinafter described.

40 The ribs 10 are equally spaced around the silo, and the panel sections therebetween comprise board sections of proper length and thickness having rounded ends fitted snugly in the grooved sides of the ribs. It 45 is to be noted however that the arc of the groove is such that the panels may be adjusted in various angular relations to the mean planes of the ribs without the edges of the ribs striking the inner or outer sides 50 of the panels. Between the ribs 10 over the panels 15 there are engaged short tie rods 34, which may be smaller than the rods 32, or of the same size, as found convenient. The rods 34 are inserted slidably through 55 the openings 18 in the lugs 17, and have nuts 35 engaged on their ends against the inner convex sides of the lugs.

In the erection of the silo, a suitable foundation is provided upon which the ribs are 60 set up in proper position and connected by the tie rods 32 and 34 so as to be held loosely in position, after which the panels 15 are put in place and the lowermost tie rods tightened somewhat. As the placing of the

panels proceeds, staging brackets 36 are engaged in the lugs 19, these brackets comprising simply rods of iron each having a short inner end portion 37 bent at right angles to the body of the bracket, which may be inserted downwardly in the openings in the 70 lugs, the horizontal portion resting at its base in the notch 21 of the lug whereby pivotal movement of the bracket is prevented. A series of the brackets is mounted on the 75 ribs at the same level, and boards 38 laid across them as shown in Fig. 4 to provide a platform, which will be ample for the needs of the work. The outer ends of the brackets are provided with small pins 39 on the upper side, by which the boards are prevented 80 from slipping off the brackets. Certain of the lower lugs 19 may be utilized to secure stay rods 40, anchored in the foundation in a suitable manner and having their upper ends inserted upwardly through the lugs and 85 secured by nuts 41.

The roof 42 may be of any suitable construction, the details of which it is not necessary to disclose herein.

It will be apparent that by the use of the 90 ribs and transverse panels therebetween, the construction of a silo may be accomplished rapidly and without special mill work in different sized structures; also, the expense of staging is eliminated by the use of the 95 brackets 36. The securing of the parts in position as erected is also simplified, and the small tie rods may be easily handled and utilized to secure the parts in position much sooner than the usual hoops can be. The 100 same sizes of ribs and panels are used for different sized silos, it being only necessary to increase or decrease the number of ribs used. The proper alignment of the ribs may be assured by an equal tightening of the nuts 105 on the rods 34. The tie rods 34, the ribs and the interposed panel pieces form a truss work, by which the walls are made very rigid and resistant to lateral deformation. That is to say, that the liability of local 110 bulging which occurs in a great many silos built of segmental staves held by hoops, will not be present in a device constructed in accordance with my invention. These tie rods 115 34 also may be used as ladders at any point around the silo when it is necessary to tighten up the nuts on the rods.

What is claimed:

A silo made up of vertical rib sections 120 which have longitudinal grooves upon the opposite edges, concaved plates seated in said grooves and projecting beyond the ends of said ribs, the outer faces of the ribs being convexed and wider than the inner faces thereof, convexed plates secured to the outer 125 convexed faces of said ribs, lugs projecting from the opposite edges of said convexed plates and having transverse apertures there-

in, rods passing through said apertures, nuts upon the rods and bearing against the lugs, superimposed panel sections having convexed ends engaging the concaved plates in 5 said grooves, and a roof fitted over the up-
permost of said panels and ribs.

In testimony whereof I have affixed my signature in presence of two witnesses.
